UNITED STATES PATENT OFFICE.

THOMAS McDONOUGH, OF OTTAWA, ILLINOIS.

LUNI-TIDAL TELLURIAN.

SPECIFICATION forming part of Letters Patent No. 674,277, dated May 14, 1901.

Application filed October 16, 1900. Serial No. 33,241. (No model.)

To all whom it may concern:

Be it known that I, THOMAS McDONOUGH, of Ottawa, in the county of Lasalle and State of Illinois, have invented a new and useful Improvement in Luni-Tidal Tellurians, of which the following is a specification.

My invention is an improved apparatus in the nature of a tellurian designed to illustrate to pupils in a simple and convincing way the cause of tides and the phases of the moon and which may be also utilized for illustrating the causes of eclipses.

It consists in the construction and arrangement of the device which I will now proceed to describe, reference being had to the accompanying drawings, in which—

Figure 1 is a face view of the instrument, showing the position of parts for new moon and showing in dotted lines the several phases of the moon. Fig. 2 is a sectional view of the same. Figs. 3 and 4 are small views illustrating the use for explaining eclipses.

In the drawings, A represents a base-board, which for convenience of transportation may be a simple flat board, preferably painted black, but for which the blackboard of the school-room may be substituted when it is not desired to move the apparatus about. In the center of the board is fixedly placed a standard B, to which is rigidly attached a bevel-wheel b. To the top of the standard B is detachably fastened by a screw a a pendant hemispherical shell C, which descends to the plane of the base-board and represents the earth.

On the standard B above the bevel-wheel b there is loosely hung an arm D, which extends out through a slot in the shell C and supports a radially-projecting shaft E, bearing on its outer end a globe M, representing the moon. The inner end of the arm D is bent to form a rectangular frame d, through the upper and lower ends of which the standard B freely passes and one side of which forms a bearing for the inner end of the radial shaft E. On the inner end of this radial shaft is rigidly keyed a bevel-wheel b', which rides upon the fixed bevel-wheel b, and as the radial shaft E is swung around the shell C, representing the earth, the shaft E is made to rotate about its axis for the purpose herein-after described.

At a suitable point on the board near the circumference described by the moon-globe M and approximately in the moon's orbit 55 there is mounted a brightly-polished plate S, representing the sun. On top of the shell C, representing the earth, there is arranged an arm F, which at one end is secured to the top of arm D and in its middle is screwed to the 60 top of the standard B, outside of the shell C, and extends upon the opposite side a considerable distance and terminates in an eye f. To this eye and to the outer end of the arm D there is attached an elliptical ring e. A 65 similar elliptical ring e' is attached to the board and incloses the earth, the major axis of said ring being on a line passing from the sun S to the earth C.

On the outer end of the shaft E is the globe C, 70 which represents the moon, and which has one half of its surface painted black and the other half, which is next to the sun gilded or painted white. As the arm bearing the moon-globe and its shaft revolves, the gear-wheel b', traveling around on the stationary wheel b, causes the moon-globe to make one complete rotation about its shaft for each complete revolution around the earth, and this causes the bright side of the moon to be always held toward 75 the sun through all the phases of the moon. Viewing the apparatus from a central position above the earth in line with the center of revolution of the moon, it will be seen that just after the moon has passed the sun, as shown 80 in full lines, a little crescent of the gilded face of the moon only will be visible from the earth, and we have what is called the "new moon." At a point No. 1, representing one-quarter of a revolution, we have the first quarter of the moon, in which one-half its surface is visible from the earth. At the position No. 2 we have the full moon on the opposite side of the earth from the sun and with all the moon's face visible from the earth. At No. 3 85 we have the last quarter, showing one-half its surface on the wane, and when the moon reaches a position in line with and between the sun and earth the full dark side of the moon will be presented to the earth and no 90 moon will be visible.

In explaining the value of the oval rings e and e' I would state that it is well known that the tides are caused by the attractive influ-

ence exerted upon the mobile waters of the earth by the sun and moon. This influence causes the waters of the earth to be heaped up on the side of the earth next to the sun and moon and also on the diametrically opposite side and to be depressed at intermediate points. This attractive influence of the moon on the water is illustrated by the oval e and of the sun by the oval e' , the ovals representing at the prolate ends of the ellipse the high tide and at the oblate or flattened sides the low tide. When the moon is in line with the sun and earth, as shown either at full moon or when the moon has its dark side to the earth, the attractive influences of the sun and moon on the water act in unison. This is shown by the two ellipses e and e' , which have their prolate ends together, and the result is the "spring tides" when the rise and fall is at its maximum. When the moon is, however, at its first and last quarter, the major axes of the two ellipses are at right angles, and as the influence of the sun is counteracted by the influence of the moon there is a minimum tide which is known as the "neap tide," which only represents the difference between the attraction of the sun and moon. Instead of the oval rings e and e' , cords, wires, or other devices may be employed to illustrate the principle in the same way.

To utilize my invention so as to employ it for illustrating the eclipses of sun or moon, the position of the sun should be removed a little farther from the earth. Then when the moon comes between the sun and the earth we have the eclipse of the sun, as seen in Fig. 3, and when the earth comes between the sun and moon we have an eclipse of the moon, as seen in Fig. 4. By means of my apparatus these usually-unintelligible phenomena are made perfectly clear and in a way so simple as to be understood even by a child.

Having thus described my invention, what I claim as new, and desire to secure by Letters Patent, is—

1. A tellurian comprising a basic support, a standard mounted thereon and bearing a hemispherical representation of the earth and a gear-wheel within it, a swinging arm mounted upon the standard, a rotating shaft sustained by said swinging arm and bearing on its outer end a globe representing the moon, one half of which is made dark and the other light, and having on its inner end a gear-wheel in mesh with and traversing the stationary gear-wheel, and a representation of the sun fixed to the basic support at a point approximately within the swing or orbit of the

moon substantially as and for the purpose described.

2. A tellurian comprising a representation of the earth, a representation of the sun remote from the earth, a representation of the moon, supporting devices for the same and means for swinging it about the earth, and two oval rings or oblong markings, the one attached to the moon-moving devices and surrounding the earth, and the other surrounding the earth in relation fixed with reference to the sun substantially as and for the purpose described.

3. The combination with the hemispherical shell C representing the earth; of a supporting-standard within the same, a swinging arm carrying on its end a representation of the moon, another arm projecting beyond the earth in the opposite direction from the moon and carrying an oblong ring or marking surrounding the earth and representing the luni-tidal influence thereupon substantially as described.

4. The combination with a base-board; of a standard bearing a rigid gear-wheel, an arm bent at its inner end to form a rectangle and having a bearing in its upper and lower ends for the standard, a rotating shaft arranged radially and supported in bearings in the outer end of the radial arm and also in the side of the rectangular frame at the inner end of the arm, and having a rigid gear-wheel on its inner end and a globe on the outer end, a hemispherical shell inclosing said gears and representing the earth, and a second arm secured to the top of the first-named arm and to the standard by a screw which also clamps and secures the hemispherical shell, substantially as shown and described.

5. A tellurian having a moon-revolving gear, a central representation of the earth, and an oval or oblong device representing the lunar tide connected to the moon-revolving gear and surrounding the earth substantially as shown and described.

6. A tellurian having a central representation of the earth, a removed representation of the sun, and an oval demarcation around the earth having its longitudinal axis in line with the sun substantially as described.

In testimony whereof I have signed my name to this specification in the presence of two subscribing witnesses.

THOMAS McDONOUGH.
